UNITED STATES PATENT OFFICE.

ALBERT C. GRUNWALD, OF CHICAGO, ILLINOIS, ASSIGNOR TO PRECISION METAL WORKERS, OF CHICAGO, ILLINOIS, A CORPORATION OF ILLINOIS.

GREASE-CUP.

1,227,130.

Specification of Letters Patent.

Patented May 22, 1917.

Application filed November 14, 1916. Serial No. 131,193.

To all whom it may concern:

Be it known that I, ALBERT C. GRUNWALD, a citizen of the United States, residing at Chicago, in the county of Cook and State of Illinois, have invented a new and useful Improvement in Grease-Cups, of which the following is a specification.

This invention relates particularly to grease-cups equipped with agitators, or feed-devices. Such a grease-cup may be mounted upon either a stationary bearing or a movable bearing. For instance, the device may be mounted upon the bearing of a connecting rod, or upon the stationary bearing of a crank-shaft. In either case, it operates successfully, owing to the normal vibration, or jar, which is incidental to the operation of any well-constructed engine, or machine.

The primary object of the invention is to provide a grease-cup of improved general construction, equipped with an agitator of improved construction.

The invention is illustrated in its preferred embodiment in the accompanying drawing, in which—

Figure 1 represents a sectional view of a bearing equipped with a grease-cup embodying the invention; Fig. 2, an inner view 30 of the grease-cup cover; Fig. 3, a perspective view showing the cover removed from the grease-cup, the latter being shown brokenly; Fig. 4, a plan sectional view showing the nipple of the grease-cup and a 35 retainer employed in connection therewith; Fig. 5, a view of a blank employed in the formation of a cone or feed-head with which the agitator-rod is equipped; Fig. 6, a sectional view of said cone in the formed condition; and Fig. 7, a view showing a modification of the cover of the grease-cup.

In the construction illustrated, the invention is shown applied to a stationary bearing, but it will be understood that it is 45 equally applicable to a movable bearing, as, for instance, the bearing of a connecting rod. In the construction illustrated, A represents a box, or bearing; B, the journal of a shaft mounted in said bearing; and C, the 50 improved grease-cup applied to the bearing A.

The device C comprises a grease-cup proper, or casing, C', equipped with a detachable cover C²; and an agitator C³ contacting with the journal B, the upper portion of the agitator having a guide formed in, or connected with, the cover C².

The grease-cup C' may be drawn from a disk of metal by suitable stamping or cupping operations. It is of the usual form and is provided at its lower end with an integrally-formed externally-threaded nipple 1, having a hexagonal portion 1^a, adapted for the application of a wrench. The bearing A has its upper portion provided with a vertical perforation 2, the upper end of which is counter-sunk and threaded to receive the threaded nipple of the grease-cup. The cap or cover C² is connected to the upper portion of the grease-cup by bayonet joint connections; and associated with the grease-cup and its cap is a spring, which serves to maintain the bayonet joint connections in interlocked relation, so that the cap will be rigidly secured to the grease-cup, but readily detachable therefrom. The bayonet joint connections, in the form illustrated, comprise a pair of studs, or internal projections, 3, with which the downturned flange of the cap C² is equipped, and a pair 80 of bayonet-slots 4, with which the upper marginal portion of the cup C' is equipped at diametrical opposite points. The bayonet slots 4 may be formed by striking the metal of the cup inwardly; and the studs 3 may be 85 formed by striking the metal of the flange of the cap C² inwardly. The bayonet slots 4 are provided with off-sets 4^a, which are recessed at their upper walls, so that the studs may interlockingly engage said recesses. 90

The cap C² is equipped internally with a leaf-spring 5, which has its central portion bowed upwardly and secured to the central portion of the cap. The leaf-spring is secured to the cap by punching a hole at the center of the cap, extending the metal through a central perforation in the leaf-spring and clenching the eyelet thus formed beneath the spring. This affords, also, a guide through which the upper portion of 100 the agitator-rod C³ extends. The ends of the leaf-spring bear upon the upper edge of

the cup C'. It will thus be understood that when the studs 3 are entered in the bayonet-slots 4 and the cap is turned to bring the studs into the off-sets 4^a, the studs will be forced, by the spring 5, to enter the recesses in the upper walls of the off-sets, so that the studs will be firmly interlocked with the bayonet-slots.

The agitator C³ comprises a rod 6, the upper end of which works through the central guide in the cap C², and the lower end of which extends through the perforation 2 and rests upon the journal B; a cone, or feed-head, 7, firmly secured to the rod 6 and preferably disposed so as to project somewhat into the nipple 1; and a light coil-spring 8 confined between the cone 7 and the cap C². The cone 7 is preferably formed from the sheet-metal blank shown in Fig. 5. The blank is in the form of a segment of an annulus, equipped with perforate ears 7^a. The annulus segment is curved to form a hollow cone, and the ears 7^a are bent across the top of the hollow cone. The head, thus formed, is slipped on to the rod 6, the perforate ears closely engaging the rod; and the cone is held in place on the rod by means of projections 9 and 10, formed by nicking the rod with a cold-chisel, or the like, at points above and below the cone. In this manner the agitator-rod is equipped with an enlargement, or feed-head, at very slight cost.

The grease-cup is locked against unscrewing by means of a retainer 11. This comprises a metal stamping having a hexagonal opening adapted to receive the hexagon 1^a of the grease-cup, and having an arm, or arms, 11^a, adapted to embrace the sides of a longitudinal embossment 12, with which the journal-box A is equipped.

In the modification shown in Fig. 7, the grease-cup C' and the agitator C³ may be of the construction heretofore described. The cap C⁴ is, however, of slightly modified form. It may be secured to the grease-cup by means of the bayonet joint construction shown in Fig. 3. It is, however, provided centrally with a hollow boss 13, by which the upper end of the agitator-rod is housed. The leaf-spring 5^a, in this case, extends across the open bottom of the cup, or embossment, 13, and is secured, by rivets 14, to the cap C⁴. At a central point, the leaf-spring is provided with a perforation, which forms a guide for the upper end of the agitator-rod. The upper end of the coil-spring 8, in this case, bears against the central portion of the leaf-spring 5^a.

In each case, the spring 8 tends to re-seat the lower end of the agitator-rod on the journal each time the agitator is raised by the vibration, or jarring action of the machine. The result is that the grease cannot

permanently raise the agitator by wedging 65 between the cone and the contracted wall at the lower end of the grease-cup.

The purpose of the agitator, of course, is to constantly keep the grease stirred up and tend to feed it slowly through the perforation 2 to the journal. Incidentally, the spring 8 co-acts with the spring 5 in holding the cap C² elevated, so that the studs C³ will be maintained in interlocking relation with the recesses in the upper walls of the off-sets 4^a of the bayonet-slots.

When desired, the grease-cup cap may be removed with great facility by pressing downwardly upon the cap and rotating it to disengage the studs 3 from the off-sets 4^a.

The foregoing detailed description has been given for clearness of understanding only, and no unnecessary limitation should be understood therefrom, but the appended claims should be construed as broadly as 85 permissible, in view of the prior art.

What I regard as new, and desire to secure by Letters Patent, is—

1. In a device of the character set forth, the combination with a grease-cup, of a 90 cap therefor provided with a downturned flange and a leaf-spring connected with said cap and bearing on the upper edge of said grease-cup, said spring having a central perforation, bayonet-joint connections between 95 the flange of said cap and the upper portion of said grease-cup, and an agitator having a stem extending through the central opening in said spring.

2. In a device of the character set forth, 100 the combination of a grease-cup provided with a nipple for attachment to a bearing, an agitator protruding through said nipple, a cap provided with a downturned flange having bayonet-joint connections with the 105 upper portion of said grease-cup, and a leaf-spring interposed between said cap and the upper edge of said grease-cup, said cap and spring having a central perforation through which the stem of said agitator protrudes. 110

3. In a grease-cup of the character set forth, an agitator comprising a rod, and a feed-head thereon comprising a segmental member of conical form equipped with perforate ears receiving and engaging said rod. 115

4. In a device of the character set forth, the combination of a grease-cup provided with a nipple and equipped with a rigidly secured detachable top, of an agitator comprising a rod protruding through said nipple, a hollow conical member secured to said rod, and a coil-spring encircling said rod and interposed between said conical member and said cap. 120

5. The combination with a journal-box 125 provided with a perforation having a threaded portion, of a grease-cup having a threaded nipple engaging the threaded por-

tion of said perforation and provided with an angular portion, an agitator in said grease-cup depending into said perforation, and a retainer having an angular opening 5 engaging the angular portion of said nipple and an arm engaging the journal-box.

6. In a device of the character set forth,

the combination with a grease-cup and a cap provided with a downturned flange having bayonet-joint connection with the upper portion of said grease-cup, of a leaf-spring within and attached to said cap and bearing on the upper edge of said grease-cup. 10
